UNITED STATES PATENT OFFICE.

CHARLES H. MAGRUDER, OF SHELBINA, MISSOURI.

MEANS FOR PREVENTING RAILS FROM SPREADING.

No. 922,928.

Specification of Letters Patent.

Patented May 25, 1909.

Application filed February 9, 1909. Serial No. 477,011.

To all whom it may concern:

Be it known that I, CHARLES H. MAGRUDER, a citizen of the United States, residing at Shelbina, in the county of Shelby and 5 State of Missouri, have invented a new and useful Means for Preventing Rails from Spreading, of which the following is a specification.

This invention relates to a novel means, 10 designed to be applied to the rails of railway tracks for the purpose of preventing the lateral spreading of said rails, and has for its object to provide a device of this character, which is simple in construction and consequently cheap to manufacture, and positive 15 in operation.

The device is adapted to be secured between any desired pair of ties, and includes rail-clamping members, which are oppositely 20 arranged on the outside of the rails and between a pair of ties, and are securely clamped to the rails by a tie bar, said bar being arranged upon a support, which also prevents the rails from being drawn too close when applying the clamp.

In the drawing:—Figure 1 is a top plan view of a railway track, showing my invention applied thereto. Fig. 2 is a side elevation of the same. Fig. 3 is a vertical transverse section, taken on the line 3—3 of Fig. 30 2. Fig. 4 is a perspective view of one of the rail-clamping members, and Fig. 5 is a perspective view of the tie bar or bolt support.

Like numerals of reference designate corresponding parts in all the figures of the drawing.

Referring to the drawing, 6 designates a plurality of ties of a railroad upon which are secured rails 7—7 by any suitable means.

40 My invention is arranged between a pair of ties at suitable intervals along the track or wherever else desired.

The invention comprises two substantially L-shaped rail-clamping members 8—8, which 45 are formed of iron or other metal, and are arranged opposite each other on the outside of the rails 7—7 and between a pair of ties. Each of these members consists of a horizontal plate 9 and a depending or vertical plate 10, the vertical plate having cut-out portions 50 11 and 12, respectively located at each end thereof. By reference to the drawing, and particularly to Figs. 1 and 2, it will be observed that the horizontal plate 9 bears upon the outside flange 13 and the web 14 of the 55 rail 7, and, furthermore, is of a sufficient

length to bridge the adjacent ties, the ends of the plate being adapted to bear upon the upper surface of the ties. The vertical plate 10 is of a length to fit snugly between, and 60 preferably extends down to the bottom of said ties, the cut-out portions 11 and 12 at each end thereof conforming to the shape of the ties.

The invention, furthermore, comprises a 65 brace 15, preferably of wood, which is arranged transversely across the track and under the rails 7—7, and the ends thereof bearing against the inner sides of the vertical plates 10—10. The base 16 of the brace is 70 preferably arranged flush with the base of the ties in order to have a solid foundation. The brace is provided on its upper surface with a longitudinal groove 17. The vertical plates 10—10 are, respectively, provided 75 with centrally arranged openings 18—18, which are in register with the groove 17 of the brace 16. A tie bar or bolt 19, which is adapted to be passed through these openings and lie in said groove, is provided at opposite 80 sides with a head 20 and a clamping nut 21. It will thus be seen that because of the brace being of a length equal to the standard railway gage, the rail-clamping members will, by means of the nut, be drawn together until 85 the said members abut against the brace. Thus the rails are prevented from any lateral spreading, either inwardly or outwardly.

From the foregoing, it is thought that the 90 construction, operation and many advantages of the herein described invention will be apparent to those skilled in the art, without further description, and it will be understood that various changes in the size, shape, proportion and minor details of construction, 95 may be resorted to without departing from the spirit or sacrificing any of the advantages of the invention.

Having thus fully described my invention, 100 what I claim as new and desire to secure by Letters Patent, is:—

1. In combination with a railroad track, of rail-clamping members oppositely arranged on the outer sides of the rails and bridging a pair of ties, a brace arranged transversely 105 across the track and under the rails, the ends thereof abutting against the rail-clamping members, a tie rod connecting said members and supported by said brace, and means arranged on the tie rod and adapted to co-act 110 with the said members and the brace for preventing lateral movement of the rails.

2. In combination with a railroad track, of rail-clamping members arranged on the outer sides of the rails, said members each consisting of a horizontal plate and a depending vertical plate, the former engaging the flange and web of the rail and bridging a pair of ties and the latter arranged between the said ties, a brace arranged transversely across the track and under the rails, the ends thereof abutting against the inner sides of the vertical plates of the rail-clamping members, a tie rod connecting said members and supported by said brace, and means arranged on the tie rod adapted to co-act with said members and brace for preventing lateral movement of the rails.
3. In combination with a railroad track, of rail-clamping members arranged on the outer sides of the rails, said members each consisting of a horizontal plate, and a depending vertical plate having a centrally arranged opening and cut-out portions at each end thereof, the horizontal plate engaging the web and flange of the rail and bridging a pair of ties and the vertical plate fitting down between the said ties, a transversely arranged brace located under the rails, the ends thereof abutting against the inner side of the vertical plates of the rail-clamping members, a longitudinal groove formed in the upper surface of said brace and registering with the centrally arranged openings in the vertical plates, a tie rod extending through the centrally arranged openings in the vertical plates and lying in the longitudinal groove of the brace, and means connected to the tie rod and co-acting with the said members and brace for preventing lateral movement of the rails.
4. In combination with a railroad track, of rail-clamping members arranged on the outer sides of the rails, said members each

consisting of a horizontal plate and a depending vertical plate, the former engaging the flange and web of the rail and bridging a pair of ties and the latter arranged between the said ties, and means connecting the rail-clamping members and arranged between the ties beneath the rails, said means including a brace arranged transversely under the rails and bearing against the vertical plates.

5. In combination with a railroad track, of rail-clamping members oppositely arranged on the outer sides of the rails and bridging a pair of ties, the ends of the said members resting on the ties and the intermediate portions of said members fitting between the ties, the ends of said intermediate portions abutting against the adjacent sides of the ties and the bottom thereof arranged substantially flush with the base of said ties, and bracing means located beneath the rails and connecting the said members.

6. In combination with the rail-clamping members arranged along the outer sides of the rails and spanning the space between two ties and resting at their ends on said ties and engaging the base flange of the rails, said members having a depending portion fitting between the ties, and bracing means connecting the clamping members and arranged transversely of the track, said means including a brace arranged under the rails and in the same plane with the ties, and bearing at its ends against the said depending portions, and a transverse tie-rod for connecting the rail-clamping members.

In testimony, that I claim the foregoing as my own, I have hereto affixed my signature in the presence of two witnesses.

C. H. MAGRUDER.
